(57) **CLAIM**

The ornamental design for a charger for vacuum cleaner, as shown and described.

DESCRIPTION

FIG. 1 is a front perspective view of a charger for vacuum cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is another perspective view thereof in an environment of use.

The broken lines illustrating portions of the charger for vacuum cleaner form no part of the claimed design. The broken lines illustrating portions of a vacuum cleaner are for illustrative purposes only and form no part of the claimed design.
